US0D1041244S

(12) **United States Design Patent** (10) **Patent No.:** **US D1,041,244 S**
(45) **Date of Patent:** **** Sep. 10, 2024**

(54) **BOTTLE LID**

(71) Applicant: **Everich And Tomic Housewares Co., Ltd.**, ZheJiang (CN)

(72) Inventor: **Huajun Yao**, Hangzhou (CN)

(***) Term: **15 Years**

(21) Appl. No.: **29/857,214**

(22) Filed: **Oct. 20, 2022**

(30) **Foreign Application Priority Data**

May 6, 2022 (CN) 202230260537.7

(51) **LOC (14) Cl.** **07-01**

(57) **CLAIM**

The ornamental design for a bottle lid, as shown and described.

DESCRIPTION

FIG. 1 is a front and top perspective view of a bottle lid, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

1 Claim, 8 Drawing Sheets
